UNITED STATES PATENT OFFICE.

MARTIN SEITZ, OF ST. LOUIS, MISSOURI.

BOWLING-ALLEY ACCESSORY.

1,139,588.

Specification of Letters Patent. Patented May 18, 1915.

Application filed January 8, 1915. Serial No. 1,149.

To all whom it may concern:

Be it known that I, MARTIN SEITZ, a citizen of the United States, residing at St. Louis, State of Missouri, have invented certain new and useful Improvements in Bowling-Alley Accessories, of which the following is a full, clear, and exact description, reference being had to the accompanying drawings, forming a part hereof.

10 My invention has relation to improvements in bowling-alley accessories; and it consists in the novel features of construction more fully set forth in the specification and pointed out in the claims.

15 The present invention relates to an attachment secured to the return-chute of bowling alleys, the object thereof being to retard the speed of the balls returned to the player by the attendant at the pit. As a 20 rule the attendant, or man at the pit who sets up the pins, throws the balls into the return-chute without regard to speed or time, the balls very often returning at a high velocity and causing a violent impact 25 against the balls already at the front end of the chute. Very often this sudden return of the balls results in the mashing of the finger of the player who has his hand on a ball he is about to pick up, while such ball 30 is still in the chute. On other occasions the impact of the returning balls against the balls at the front end of the chute is so violent as to form dents in the balls, or may even result in the chipping of the ball 35 around the sockets with which many of them are provided for the insertion of the finger.

The object of the present attachment therefore is to retard the speed of the returning ball so that all the balls returned 40 may roll back gently and without danger of the evil consequences pointed out above.

45 The advantages of the invention will become clearly apparent from the detailed description which follows in connection with the accompanying drawings in which—

50 Figure 1 is a perspective view of a section of a return chute showing my invention applied thereto; Fig. 2 is an outer face elevation of one of the brackets and hinged arm coupled thereto, the arm having been partly deflected outwardly to illustrate the free play of the guide-stem through the rocker-bearing of the bracket; Fig. 3 is a vertical cross-section on the line 3—3 of Fig. 2; Fig. 55 4 is a top plan of a portion of the return

chute, and the device attached thereto illustrating the manner of deflection of the retarding arm by a rolling ball; and Fig. 5 is a diagrammatic cross-section of a modification of the invention.

Referring to the drawings, and for the present to Figs. 1 to 4 inclusive, C represents a conventional return-chute for bowling-alley balls, as well understood in the art. Secured to the opposite sides of the chute at a convenient point along the length thereof, and transversely opposite to one another, are brackets 1, 1, which are bent so as to bring their upper portions outside the planes of the side walls of the chute, the brackets being preferably provided with knobs or bosses *a* set into corresponding sockets of the chute to reduce the strain imposed on the securing screws *s* by which the bracket is fastened to the chute. Disposed on the opposite edges of each bracket (both brackets being alike) are perforated ears or loops 2 for receiving a hinge-pin 3, said pin being likewise received by the terminal registering loops 2' of an oscillating arm 4 hinged to the bracket about one of the loops. By providing each bracket with two loops 2, one on each side, any bracket may be secured indiscriminately to either side of the chute, and the proper loop utilized for hinging the arm 4 thereto, it being understood that the arm 4 is hinged to the loop on the side which is toward the player's end of the chute (Fig. 1). The inner face of each arm 4 is preferably lined with leather *m* or equivalent material so as to present a smooth riding surface to the periphery of the ball *B* passing between the arms 4, 4, disposed on opposite sides thereof. Projecting from the bracket 1 along a center line thereof between the ears or loops 2, 2, are a pair of posts 5, 5, between the free ends of which is rotatably mounted a bearing 6, the same being supported by screw spindles 7, 7, inserted through the posts and entering suitable sockets or depressions in the bearing as shown (Fig. 3). The rotatable or rocker-bearing 6 is freely traversed by the outer end of a stem 8 terminating in a head *h*, the inner portion of the stem being somewhat reduced in cross-section and screw-threaded, the free end of the screw-threaded portion being flattened (Fig. 2) and pivotally coupled by means of a split pin 9 between a pair of lugs 10, 10, projecting from the outer face of the arm 4 adjacent the free

end of a stem 8 terminating in a head h , the 60
8 is a ring or adjustable abutment 11 between
which and the bearing 6 (which
serves as a stationary abutment) is con-
fined an expansion spring 12 coiled about
the stem 8, the tendency of the spring being
to force the arm 4 inwardly or toward the
axis of the return chute C (Fig. 4). The
tension of the spring 12 may be carefully
regulated by the lock-nuts t , t , operating
over the screw-threaded portion of the stem
8, as obvious from the drawing (Fig. 4).

The operation will be apparent from the
previous description, and may be briefly
summarized as follows: With a bracket 1
secured on each side of the run-way of the
chute C, and with the arms 4, 4, hinged on
the side facing the player, the opposing
arms will converge toward the axis of the
run-way (Figs. 1, 4,) and present their in-
ner faces to the ball B as the latter is roll-
ing down (or along) the chute. The balls
rolling in the direction indicated by the
arrows (Figs. 1, 4,) will thus be obliged to
pass between the retarding arms 4, 4, which
are yieldingly held in the path of the ball,
and as the successive balls strike the arms,
their weight and momentum effect a dis-
placement of the arms causing the latter to
diverge or open outwardly to let the ball
pass. The ball by its impact against the
yielding arms loses considerable of its mo-
mentum, and after it has passed the arms
it rolls gently to the player's end of the
chute without jar or damage. After a ball
passes the arms, the springs 12 (which were
under more or less compression under the
opening movement or oscillations of the
arms) by their expansion to restore the arms
to their normal or "closed" position to re-
ceive the next ball, and so on. The arms
4, 4, therefore act as retarders or brakes to
prevent the injurious effects of too great
momentum of the balls returned by the man
45 at the pit.

In the form of the invention thus far de-
scribed, I have assumed that two arms are
used, one on each side of the ball; and
while that is the preferred construction, it
50 is possible to utilize a single arm where one
wall of the chute affords a bearing to one
side of the ball. Such a modification is
shown diagrammatically in Fig. 5 where
the chute C' has a wall w extended upward
55 on one side of the run-way to afford a bear-
ing for the ball B while the opposite side
is engaged by a single yielding arm 4 as pre-
viously described.

The invention may be applied to any chute

on the market, the precise position and man- 60
ner of attaching the retarding device being
left to the judgment and discretion of the
skilled mechanic.

Having described my invention what I
claim is:

1. In combination with a bowling-alley
return-chute, traversed by a ball, a pair of
spring-controlled laterally oscillating mem- 70
bers yieldingly engaging the surface of the
ball from opposite sides, during the travel
of the ball, whereby the velocity of the ball
is retarded.

2. In combination with a bowling-alley
return-chute, traversed by a ball, a bracket
securable to the side of the chute and pro- 75
jecting above the chute, an arm hinged to
said bracket and extending across the path
of the ball traversing the chute, a pair of
posts projecting from the outer face of the
bracket at a point opposite the hinge-axis 80
of the arm, a rocker-bearing mounted be-
tween the posts a suitable distance from the
bracket, a stem leading from said rocker-
bearing to a point adjacent the free end of
the arm and pivotally coupled to said arm, 85
said stem having a screw-threaded portion
adjacent its point of connection with the
arm, a ring passed loosely over the stem, a
spring coiled about the stem and interposed
between the ring and the rocker-bearing, 90
and adjusting nuts on the threaded portion
of the stem engaging the ring and regulat-
ing the tension of the spring.

3. A bowling-alley return-chute attach- 95
ment comprising a bracket securable to the
chute-wall, perforated ears or loops dis-
posed on each side of the bracket, a pair
of posts projecting from the outer face of
the bracket at a point intermediate the 100
loops, an arm hinged to one of the loops
aforesaid, a rocker bearing between the
posts, screw-studs or spindles passed through
the posts for supporting the rocker-bearing,
a stem centrally traversing the rocker-bear- 105
ing, and extending therefrom along the out-
side of the arm and oscillatable conjointly
therewith, the end of the stem opposite the
rockers-bearing being pivotally coupled to
the arm, an adjustable abutment on the 110
stem, and a spring coiled about the stem and
having its ends bearing respectively against
the abutment and rocker-bearing.

In testimony whereof I affix my signa-
ture, in presence of two witnesses.

MARTIN SEITZ.
